UNITED STATES PATENT OFFICE.

ALLEN L. McCORMICK, OF LOUISVILLE, KENTUCKY.

WEATHER-STRIP FOR WIND-SHIELDS OF AUTOMOBILES.

REISSUED

1,107,819.

Specification of Letters Patent. Patented Aug. 18, 1914.

Application filed December 8, 1913. Serial No. 805,395.

To all whom it may concern:

Be it known that I, ALLEN L. McCORMICK, a citizen of the United States, residing at Louisville, in the county of Jefferson, 5 State of Kentucky, have invented certain new and useful Improvements in Weather-Strips for Wind-Shields of Automobiles; and I do hereby declare the following to be a full, clear, and exact description of the invention, such as will enable others skilled in the art to which it appertains to make and use the same.

The present invention is directed to weather strips for wind shields for automobiles, and has for its object to provide an article of this type which may be quickly applied to the wind shield to prevent rain from entering the space between the opposing edges of the upper and lower glass sections.

A further object of this invention is to so construct a device of this type which when in place will prevent rain from beating through the shield, the same being formed from rubber so that it may be easily applied, and when in place will in no way injure the glass panes of the shield.

With these and other objects in view, this invention resides in the novel features of construction, formation, combination and arrangement of parts to be hereinafter more fully described, claimed and illustrated in the accompanying drawing, in which:

Figure 1 is a perspective view of a wind shield showing the device in place. Fig. 2 is a sectional view on line 2--2 of Fig. 1. Fig. 3 is a fragmentary perspective view of the device.

Referring to the drawing, the numeral 1 designates the wind shield, comprising the upper and lower hingedly connected sections 2 and 3, respectively for supporting the glass panes 4, 4'. A stopper 5 is formed from a single piece of comparatively soft rubber molded so as to provide a web 6 substantially the same length as the space 7 formed between the opposing edges of the panes 4 and 4'. The inner edge of the web 6 terminates in a rib 8, which is circular in cross section, and of the same length as the web 6. The forward edge of the web 6 ter-

minates in oppositely directed flanges 9, said flanges being curved inwardly so that the upper edge of the uppermost flange will bear against the outer surface of the pane 4 and 55 the lower edge of the lowermost flange will bear against the pane 4', said flanges being of the same length as the web 6. From this construction it will be seen that when the wind shield 1 is in its operative position that 60 the web 6 will occupy the space between the opposing edges of the panes 4 and 4', and that the rib 8 will engage the inner surfaces of the panes 4 and 4' adjacent the space 7, and the curved flanges 9 will engage the 65 outer surfaces of the panes 4 and 4' in such a manner as to prevent rain from entering the space 7. By curving the flanges 9 it is obvious that there will be a tendency to draw the rib 8 tightly against the inner 70 surfaces of the panes 4 and 4' with the result that the edges of the flanges 9 will bear tightly against the outer surfaces of the panes, thus insuring a water-tight joint.

From the foregoing description it will be 75 seen that a device has been provided to prevent leakage of water at the point where the glass panes have their edges opposed and spaced, and that the device is exceedingly simple in construction and one which can be 80 manufactured at a very small cost.

What is claimed is:

In combination with a wind shield comprising upper and lower sections, glass panes carried by the sections and having 85 their opposing edges spaced apart, of a strip formed from rubber and comprising a web for occupying the space between the opposing edges of the panes, the inner edge of said web terminating in a rib for engaging 90 the inner surfaces of the panes, said web having its outer edge terminating in oppositely directed flanges, said flanges being curved inwardly and having their edges engaging the outer surfaces of the panes, as 95 and for the purpose set forth.

In testimony whereof, I affix my signature, in the presence of two witnesses.

ALLEN L. McCORMICK.

Witnesses:

T. J. MILLS,

CARL G. REIMERS.
